UNITED STATES PATENT OFFICE.

GEORGE E. BISHOP, OF CLEVELAND, OHIO.

AUTOMOBILE-DOOR CURTAIN.

1,244,692.

Specification of Letters Patent. Patented Oct. 30, 1917.

Application filed August 10, 1916. Serial No. 114,228.

To all whom it may concern:

Be it known that I, GEORGE E. BISHOP, a citizen of the United States, resident of Cleveland, county of Cuyahoga, and State of Ohio, have invented new and useful Improvements in Automobile-Door Curtains, of which the following is a specification, the principle of the invention being herein explained and the best mode in which I have 10 contemplated applying that principle, so as to distinguish it from other inventions.

My invention relates to curtains and particularly to curtains for use upon an automobile. More particularly, my invention 15 relates to door curtains in which the curtain fabric can be supported upon a frame which provides an integral self-contained support for holding and stretching the fabric and which can be readily collapsed and rolled 20 or folded up with the fabric when the curtain is not in use. For illustration, the construction of the frame is such as to provide the advantages aforementioned in connection with the well-known type of curtain 25 known as the "jiffy" curtain which is provided with a plurality of long narrow transparencies. Thus the curtain can be folded into a bundle of a width substantially corresponding to that comprehended by one of 30 the transparencies. Furthermore, my invention relates to vehicle inclosures, in which a curtain is constructed consisting of a door portion and a portion disposed laterally of the door portion, in combination 35 with a valance which is adapted to be detachably secured to the canopy frame and thus removably secure the inclosure as a whole to the vehicle, said valance comprising a portion which is integrally connected 40 to the curtain proper and another portion which is separable from the curtain proper at or about the line of the break, all as hereinafter fully explained.

The annexed drawings and the following 45 description set forth in detail certain means embodying my invention, such disclosed means, however, constituting but one of the various forms in which said invention may be exemplified.

50 In said annexed drawings;

Figure 1 represents a broken elevation of the side of an automobile showing my improved curtain carried upon the rear door thereof; also, a suggestion of the front door 55 and a curtain; Fig. 2 represents the automobile door and curtain of Fig. 1 in an

open position; Fig. 3 represents a broken elevation of the curtain fabric and the elements of my invention utilized for stretching said fabric; Fig. 4 represents a plan view and horizontal section taken in the plane indicated by line 4—4, Fig. 3; Fig. 5 represents a vertical section taken in the plane indicated by line 5—5, Fig. 3; and Fig. 6 represents a broken elevation, taken 60 from the opposite side of the view shown in Fig. 3, of the elements of my invention utilized for stretching the curtain fabric.

In the annexed drawings, 1 represents the body of an automobile provided with a top 70 2 and the quarter 2', as plainly indicated in Figs. 1 and 2. The automobile doors are represented at 3. My improved door curtain comprises the fabric portion 4 with which are incorporated the transparencies 5, 75 in the form illustrated in the drawings, being the well-known "jiffy" type of curtain. The self-contained supporting frame for said curtain fabric 4 comprises vertical bars 6 and 7, the same, in the form of device 80 shown, being incorporated with said fabric and a stretching member 8 made in two parts 9 and 10, in the form illustrated, said two parts being pivoted at 11 and 12, respectively, to the two vertical bars 6 and 7, 85 as plainly shown in Figs. 2 and 3. As is plainly shown in Fig. 3, the bar 6 is provided with a U-shaped lug 6' rigidly secured thereto and within which the part 9 of the stretching member 8 is pivoted. Part 90 9 is formed with an elongated slot 13 approximately centrally of its ends and with a lug 14 at its inner end. The part 10 is provided with a handle 15 pivoted thereto and is also formed with a plurality of holes 95 16 so positioned as to be capable of alignment with and to receive the lug 14. The pivoted handle 15 is formed with an elongated head 17 capable, in certain positions of the pivoted handle 15, of being passed 100 through the elongated slot 13.

The curtain fabric 4 is formed with an extension 18 disposed laterally of the door opening and adapted to provide curtain protection intermediately of the automobile 105 doors and forwardly of the rear door upon which the inclosure is shown in the form and use of the invention illustrated in the accompanying drawings. There is also provided, in combination with the curtain 110 proper, to form the complete inclosure, a valance 19 which effectively closes the joint

at the quarter 2', affording complete protection from all untoward weather conditions, as plainly shown in Figs. 1 and 2, without great inconvenience in providing such an effective joint every time the door is opened and closed. This valance member 19 is adapted to be removably secured to the canopy by the end buttons 20 and the intermediate button 20', the latter button being disposed at or about the line of the desired break in the curtain when the door is open. The inclosure as a whole is connected to the automobile frame by said fasteners 20 and 20' so that both the curtain proper and the valance are removed from the frame by unfastening said connections. This valance member 19 is comprised of two portions, one of which is disposed above the integral extension 18 of the curtain proper and is integrally attached to said extension to a point at or about the line of the door hinges, the other portion of the valance being disposed above the door heading so as to complete the door effect of the curtain and being separable from the main portion 4 of the curtain when the door is open, as shown in Fig. 2. This last-named portion of the valance 19 forms a bumper against which the upper edge of the door portion 4 of the curtain contacts when the door is closed, thus providing a perfect joint. If found desirable, the connection 20' might be omitted, in which case the valance portion disposed above the lateral extension 18 would be considerably shortened so that the support necessary for making the break to create the upper fabric hinge would be perfectly maintained. By "upper fabric hinge," it is meant that the curtain portions are in reality parts of a door, and in combination with the door 3 makes a complete inclosure for the door opening and the entire space above said opening up to the quarter 2', which inclosure has an upper fabric hinge at or about the connection 20' and two lower metal hinges, as plainly shown upon the door 3, Fig. 1. The rod 6 is incorporated with the curtain fabric 4 at one end of the fabric 4, which rod extends beyond the edge of the automobile door 3, thus producing a close lapping of the door curtain against the main curtain 21 when the automobile door is closed.

It is apparent from the construction shown and described that according to the necessities of the case, the lug 14 can be inserted in the desirable hole of the series of holes 16 and the pivoted handle 15 actuated to secure the passage of the elongated head 17 through the slot 13, and then the handle turned to lock securely together the two parts 9 and 10 of the stretching member. This locking and stretching action is effected when the handle 15 is in the positions shown in Figs. 3 and 6, so that said handle can be

utilized as a member to support the curtain on the automobile door as is plainly indicated in Fig. 5, wherein is shown the door formed with a slot 23 and provided with a bearing 24. The handle 15, slot 23 and member 24 are circular in cross-section. It is apparent that when the door-curtain is removed from the door and the handle 15 actuated to effect the unlocking of the two parts 9 and 10 of the stretching member, that said two parts can be positioned parallel with the respective vertical bars 6 and 7 and rolled up with or folded in the curtain.

It will be noted that the automobile door, as shown in Fig. 2, is so hung that it slopes materially downwardly when open, as plainly shown in said Fig. 2. This produces a line of breakage in the curtain approximately that shown by the dotted line 22, Fig. 1. My improved curtain readily produces a distinct line of breakage when the automobile door is open, whether the door is hung so as to slope when open or so as to swing in horizontal planes. Also, the distance by which the automobile top 2 overhangs the automobile body 1 effects the location of the line of breakage of the curtain when the door is open and my improved curtain will operate satisfactorily whether the amount of this over-hanging be great or small.

My improved door curtain is self-contained and maintains its integrity thoroughly by means of the stretching frame hereinbefore described, as well as producing tight joints with all contiguous parts of the other automobile curtains and top.

What I claim is:

1. In an automobile curtain, the combination with suitable curtain fabric; of a collapsible frame supporting the latter, said frame comprising a pair of strengthening members, a stretching member pivoted to said strengthening members, and a third member for attaching said supporting frame to an automobile door, said third member and stretching member being provided with co-operating connecting elements, respectively, whereby the same may be connected or detached and the relative pivotal movement of said stretching member and strengthening members prevented or allowed.

2. In an automobile curtain, the combination with suitable curtain fabric; of a frame supporting the latter comprising strengthening members, a two-part stretching member pivoted to some of said strengthening members and provided with means for preventing relative longitudinal movement of said two parts, one of the two parts of said stretching member being formed with a slot therethrough, and the other part being provided with a head pivotally mounted rela-

tively thereto and adapted to pass through said slot only in certain positions, and means for attaching said supporting frame to an automobile door, said latter means adapted to control the movements of said pivoted head and hence the integrity and collapsing of said two-part stretching member.

3. In an automobile curtain, the combination with suitable curtain fabric; of a frame supporting the latter comprising a pair of strengthening members incorporated in said fabric, a two-part stretching member pivoted at its ends, respectively, to said strengthening members and provided with means for preventing the relative longitudinal movement of said two parts, one of the two parts of said stretching member being formed with an elongated slot therethrough, and the other part being provided with a handle pivoted thereto and formed with an elongated head adapted to pass through said slot only when said pivoted handle is in certain positions, said pivoted handle being also the means for attaching said supporting frame to an automobile door.

4. In an automobile curtain, the combination with suitable curtain fabric; of a frame supporting the latter comprising vertical strengthening members incorporated with said fabric, a horizontal two-part stretching member pivoted at its ends, respectively, to two of said vertical members, one of the two parts of said stretching member being formed with an elongated slot therethrough and a lug, and the other part being provided with a handle pivoted thereto and formed with an elongated head adapted to pass through said slot only when said pivoted handle is in certain positions, said second-described part of said stretching member being formed also with a series of holes adapted to be aligned with, and to receive

said lug, said pivoted handle being also the means for attaching said supporting frame to an automobile door.

5. A curtain constructed for use as a vehicle door, consisting of a main member and an auxiliary member, portions of said two members constituting a valance which is detachably secured to the canopy frame, said valance comprising a portion which is an integral part of said curtain auxiliary member, and a portion which is separable, at or about the line of the door break, from the remainder of the curtain main member and forms a bumper for the latter when the curtain is closed, whereby said curtain is removable as a whole and said main member may be opened and closed without disturbing its valance portion.

6. A vehicle inclosure consisting of a curtain comprising a door portion and a portion disposed laterally of said door portion, in combination with a valance which is detachably secured to the canopy frame and comprises a portion integrally secured to said lateral curtain portion and a portion disposed above the door heading to complete the door effect of the curtain, separable, at or about the line of the door break, from the door portion of said curtain, and forming a bumper against which the upper edge of said door portion closes, whereby said curtain and valance are removable together as a whole and said door portion of said curtain may be opened and closed without disturbing said valance.

In testimony whereof, I have signed this specification on this 9th day of August, 1916.

GEORGE E. BISHOP.
